UNITED STATES PATENT OFFICE

STEPHEN G. BLESSINGTON, OF CLAREMONT, NEW HAMPSHIRE

TAPE ATTACHING MACHINE

Application filed May 1, 1928. Serial No. 274,290.

This invention relates to a machine for attaching tape to the uppers of boots and shoes, and while the machine is particularly adapted for this purpose, it is to be understood that it may also be used for attaching tape to sheet material other than the uppers of boots and shoes.

The object of the invention is to provide a machine which will attach tape to the uppers of boots and shoes and is also adapted to be manually operated to cut the tape whenever desired without stopping the machine.

The object of the invention is also to provide means whereby the tape can be automatically fed to the tape attaching instrumentalities after it has been severed.

With these objects in view the invention consists in the combination and arrangement of parts set forth in the following specification and particularly pointed out in the claims thereof.

Referring to the drawings:

Figure 1 is a front elevation, partly in section, of my improved tape attaching machine.

Fig. 2 is a side elevation of the same.

Fig. 3 is a sectional plan illustrating the cutting and tape feeding instrumentalities.

Figs. 4, 5, 6 and 7 are detail front elevations illustrating the tape attaching, cutting and feeding instrumentalities in different position relatively to each other.

Fig. 8 is a portion of an upper with reinforcing tape attached thereto.

Like numerals refer to like parts throughout the several views of the drawings.

In the drawings, 10 is the frame of the machine. 11 is a driving shaft. 12 is a driving pulley, the same being rotated by a belt 13. 14 is a work support. 15 is a feed plate upon which the upper rests as the tape is being attached thereto. A reciprocatory motion is imparted to the feed plate, which cooperates with a gripper 16. The feed plate 15 is mounted upon a rocker frame 17 which is pivoted at 18 to the frame of the machine and has a rocking motion imparted thereto about said pivot by a cam 19 which is fast to the shaft 11 and is rotated thereby, thus imparting to the feed plate a reciprocatory move-

ment longitudinally of the tape which is being attached to the upper.

The feed plate 15 is positioned beneath the upper, and the gripper 16 is positioned above the upper and has a four motion imparted thereto, the gripper 16 is fast to a rod 22 which forms in effect a part thereof and slides in a bearing 20 formed in the end of an arm 21 which forms a portion of the rocker frame 17. A vertical motion is imparted to the gripper by the rod 22 to which it is fastened and which has a reciprocatory motion imparted thereto, and which is reciprocated vertically in the bearing 20 by a link 23 which is pivoted at 24 to a block 25 fast to the upper end of the rod 22. The upper end of the link 23 is pivoted at 26 to an arm 27 of a bell-crank lever 28 which is pivoted at 29 to a block 30 fast to a rod 31 which is slidably mounted in the frame 10 and has a presser foot 32 fast to its lower end, this presser foot being adapted to press against the tape and bring it into close contact with the upper as it rests upon the feed plate 15, and this presser foot further holds the tape and upper in position upon the return movement of the upper feeding instrumentalities, namely, the plate 15 and the gripper 16.

A spring 33 bears against the upper side of the block 30 and at its upper end bears against the frame of the machine. Another spring 34 bears at its upper end against the block 30 and at its lower end against the frame of the machine, so that the block is interposed between two springs 33 and 34.

The bell-crank lever 28 is provided with a vertical arm 35 which is connected at its upper end by a link 36 to an eccentric pin 37 fast to a disc 38 which, in turn, is fast to and is rotated by the shaft 11, which rotates in the direction of the arrow *a*, Fig. 1.

The mechanism just described and herein-after more fully described as to its operation, constitutes the mechanism for feeding the upper with the tape attached thereto, and also for pressing the tape, which is an adhesive tape, against the upper, so that it will adhere thereto.

A reinforcing tape, Fig. 4, is fed to the upper feed instrumentalities through a tape

guide 40 which is fastened to an arm 41 which is rigidly fastened to and forms in effect a portion of an arm 42, the arm 42 being provided with a hub 43 pivoted to rock upon a stud 44 which is fast to the frame of the machine.

The tape is severed by a pair of cutters, an upper cutter 45 and a lower cutter 46. The upper cutter 45 is fastened to a rocker arm 47 which is pivoted at 48 to the frame of the machine. The lower cutter 46 is fastened to a downwardly projecting arm 49 on a rocker frame 50 which is pivoted at 51 to the frame of the machine on opposite sides of the head 52 of said frame.

A rocking motion is imparted to the rocker frame 50 by the arm 47 which is connected thereto by a link 53, the lower end of which is pivotally connected to the arm 47 at 54 and the upper end is connected to arm 49 by a pivot 55.

A rocking motion is imparted to the rocker arm 47 by a link 56 which is pivotally connected at its upper end at 57 to the lower end of an arm 58. The arm 58 is rotatably mounted at 59 upon a bracket 60 which is fast to the frame of the machine and a rocking motion is imparted to the arm 58 by an arm 61 which is fastened thereto and is manually operated by means of a handle 62.

The rocker arm 47 has an arm 63 projecting upwardly therefrom, which is provided with a stop screw 64 which is brought to bear against the frame 10 by a spring 65, one end of which is fastened to the arm 58 at 66, the other end being fastened to the frame at 67. The rocker arm 47 has a horizontal, laterally extending pin 68 fast thereto which, upon the downward movement of the rocker arm 47 engages an inclined face 69 upon a cam plate 70. The cam plate 70 is fast to the arm 42 and the said cam plate is held against the pin 68 by a spring 71, one end of which is fastened to a pin 72 which, in turn, is fastened to the arm 41 and hence to the arm 42, the other end of which is fastened to a pin 73 which is fastened to the frame of the machine. Thus the cam plate 70 is kept in contact with the pin 68 and the rocking of the arm 47 upon its pivot 48 will thus, through the pin 68, impart a rocking movement to the arm 42 and to the tape guide 40 which is attached to it through the arm 41. A stop 42 engages the arm 42 to limit its movement by the spring 71.

The general operation of the mechanism hereinbefore described is as follows:— Assuming the different feeding and cutting instrumentalities to be positioned relatively to each other, as illustrated in Fig. 4. At that time the tape 39 is being pressed against the upper 74 by the gripper 16 and presser foot 32, as illustrated in Fig. 4. The cutters 45 and 46 are in the relative positions illustrated in Fig. 4 and also in Fig. 2, that is, the upper

cutter 45 is raised away from the work and the lower cutter 46 is moved backwardly from beneath the tape 39. The operator now depresses the arm 62, thus rocking the arm 58 toward the front of the machine, see Fig. 2, 70

and through the link 56, the arm 47 with the cutter 45 thereon, is moved downwardly to engage the lower cutter 46 which is moved forwardly beneath the tape. The front end of the cutter 46 is moved approximately in a horizontal path, due to the fact that it is supported upon the rocker frame 50 and the rocker frame 50 is pivoted at 51, so that the forward end of the cutter is positioned approximately directly beneath the pivot 51 80

and hence, when the rocker frame 50 is rocked upon its pivot by the arm 47 and link 53, the forward end of the cutter 46 will be moved in approximately a horizontal path and will be brought beneath the tape 39 in readiness for it to be severed as illustrated in Fig. 5, 90

at the same time the tape guide 40 is moved backwardly or toward the right from the position illustrated in Fig. 4 to the position illustrated in Fig. 5, thus drawing out a new supply of tape from the end of the tape guide adjacent to the cutters and this supply of tape is illustrated in Fig. 6 projecting from the end of the tape guide 40 and wherein the cutters have completed the severing of the tape. The cutters then open and the tape guide moves forward, positions the end of the tape beneath the gripper, the presser at this time holding the upper against the work tape. The gripper and the feed plate now move to the left, the presser foot being raised to allow the upper to be fed with the tape, and the parts are then in the relative positions illustrated in Fig. 4. During the feeding of the tape and the upper, the presser foot is released to allow this feeding to take place. As soon as the cutters are opened it will be understood that the tape guide moves forward to the position illustrated in Fig. 4 ready to again draw backwardly in order to present a free end of tape and position the same beneath the gripper after the severing operation has taken place.

The mechanism for operating the presser foot 32 and the gripper 16 and feed plate 15 are similar to the mechanism for operating the presser foot, the needle and the work supporting and feeding plate in a Singer sewing machine, and it will be seen that as the eccentric pin 37 is moved in the direction of the arrow α , the bell-crank lever 28 will be rocked to raise and lower the gripper 16 and also the presser foot 32, the parts being so adjusted that when the gripper is moved downwardly to grip the stock between it and the feed plate 15, a further movement of the eccentric pin 37 in the direction of the arrow α will cause the pivot 29 to be raised slightly, due to the fact that the gripper 16 cannot be moved any fur- 120

ther downwardly and, therefore, a pull on the link 36 will cause the bell-crank lever 28 to pivot about the pivot 26 and thus lift the arm 27 and the pivot 29 and raise the block 30 compressing the spring 33 and allowing the spring 34 to expand, and at the same time will raise the presser foot 32 sufficiently for the stock to be fed by the gripper 16 and the feed plate.

I claim:

- 10 1. A tape attaching and severing machine having, in combination, mechanism for attaching a strip of adhesive tape to a piece of sheet material, mechanism to intermittently feed said sheet material with a tape attached thereto, a tape guide, a rocker arm, a cutter fast thereto and positioned above the tape, a rocker frame, a second cutter fast to said rocker frame and positioned beneath the tape and connected to said rocker arm, said rocker arm and rocker frame being relatively so pivotally mounted that downward movement of the upper cutter will cause the lower cutter to be moved beneath the tape and the tape to be severed by said cutters.
- 15 2. A tape attaching and severing machine having, in combination, mechanism for attaching a strip of adhesive tape to a piece of sheet material, mechanism to intermittently feed said sheet material with a tape attached thereto, a tape guide, a rocker arm, a cutter fast thereto and positioned above the tape, a rocker frame, a second cutter fast to said rocker frame and positioned beneath the tape and connected to said rocker arm, said rocker arm and rocker frame being relatively so pivotally mounted that downward movement of the upper cutter will cause the lower cutter to be moved beneath the tape and the tape to be severed by said cutters, said tape guide
- 20 being mounted on a second rocker arm pivotally mounted to swing in a plane transversely of the cutting edges of said cutters, and means on said first-named rocker arm adapted to engage the second rocker arm and
- 25 cause it to be moved toward and away from said upper feeding mechanism whereby the tape may be severed, the severed end caused to assume an advance position relatively to the tape guide and the severed end fed by the
- 30 tape guide to the sheet material feeding mechanism.

In testimony whereof I have hereunto set my hand.

STEPHEN G. BLESSINGTON.
